UNITED STATES PATENT OFFICE.

WILLIAM G. PANCOAST AND WILLIAM J. GROTHUIS, OF CHICAGO, ILLINOIS,
ASSIGNORS TO BIFLEX PRODUCTS COMPANY, OF WAUKEGAN, ILLINOIS, A
CORPORATION OF ILLINOIS.

DESIGN FOR AN AUTOMOBILE-BUMPER.

55,484.

Specification for Design.

Patented June 15, 1920.

Application filed February 21, 1920. Serial No. 360,399. Term of patent 14 years.

To all whom it may concern:

Be it known that we, WILLIAM G. PANCOAST and WILLIAM J. GROTHUIS, citizens of the United States, residing at Chicago, in the county of Cook and State of Illinois, have invented a new, original, and ornamental Design for an Automobile-Bumper, of which the following is a specification, reference being had to the accompanying drawing, forming a part thereof.

The figure is a front view in elevation of

an automobile bumper, showing our new design.

We claim:

The ornamental design for an automobile bumper, as shown.

WILLIAM G. PANCOAST.

WILLIAM J. GROTHUIS.
